UNITED STATES PATENT OFFICE

GUY M. BARBER, OF LOS ANGELES, CALIFORNIA, ASSIGNOR OF ONE THIRD TO WILLIAM McDONALD WOOTTON, OF LOS ANGELES, CALIFORNIA.

HYDROCARBON BURNER

1,251,952.

Specification of Letters Patent.

Patented Jan. 1, 1918.

Application filed March 22, 1917. Serial No. 156,995.

To all whom it may concern:

Be it known that I, GUY M. BARBER, a citizen of the United States, residing at Los Angeles, in the county of Los Angeles and State of California, have invented a new and useful Hydrocarbon Burner, of which the following is a specification:

The present invention appertains to hydrocarbon burners, and aims to provide a novel and improved device of that character for burning gas, oil or other hydrocarbon fuel, the burner being adapted for use in a furnace, stove or the like.

It is the object of the invention to provide a hydrocarbon burner embodying a novel assemblage of the component elements, and having improved features of construction to enhance the utility and efficiency thereof.

With the foregoing and other objects in view which will appear as the description proceeds, the invention resides in the combination and arrangement of parts and in the details of construction, hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a plan view of the burner.

Fig. 2 is a vertical diametrical section taken on the line 2—2 of Fig. 1.

Fig. 3 is a section taken on the line 3—3 of Fig. 2.

Fig. 4 is a sectional detail illustrating a modification.

The burner embodies a horizontal disk or plate 1 adapted to be seated in a stove, furnace, or the like, and composed of suitable material to resist the heat to which it is subjected, the plate 1 having a central opening 2 and an annular series of upstanding radial ribs 3 surrounding said opening and provided at their outer ends with upstanding lugs 4 for holding in place, a disk-shaped or circular deflector plate 5 seated on the ribs 3 over the opening 2. The deflector 5 is contracted or slightly dome-shaped, and is provided at its edge with an upstanding marginal flange or rib 6 providing an annular trough. The plate 1 is also preferably provided with an annular series of upstand-

ing radial ribs 7 near its edge, and alternating with or being in staggered arrangement relative to the ribs 4 as seen in Fig. 1.

Suspended from the plate 1 is a vertical tubular member or sleeve 8 having its upper end fitted within the opening 2 and provided with a flange 9 seated on the plate 1. This sleeve 8 provides a mixing chamber whose upper end is open underneath the deflector 5. A ring 10 is screwed on or otherwise engaged on the lower end of the sleeve 8 and is provided with a depending or dropped spider 11, the hub of which is provided with an open slot 12. Air upstanding pressure fluid nozzle 13 is seated on the hub of the spider and its upper end projects into the lower end of the sleeve 8 centrally thereof. A supply pipe 14 for steam, compressed air or other pressure fluid is attached to one side of the nozzle 13 for supplying the pressure fluid thereto, and an upstanding or vertical fuel nozzle 15 for gas or other fuel extends upwardly through the lower closed end of the nozzle 13, the nozzle 15 being engaged with the lower end of the nozzle 13 and a nut 16 or other retaining means being engaged upon the nozzle 15 and bearing upwardly against the hub of the spider 11, whereby to clamp the nozzles 13 and 15 in place. When the nut 16 is loosened, the nozzle 15 which extends through the slot 12 can be withdrawn therefrom, to enable the parts to be readily separated and assembled. The nozzle 15 is provided with a head or tip 17 within the upper open end of the nozzle 13, and said tip has spiral grooves 18 for the flow of pressure fluid upwardly past the delivery end of the nozzle 15, whereby the pressure fluid is given a whirling motion to atomize and mix the fuel, the fuel being sucked or drawn from the nozzle or tube 15.

A collar or nipple 19 is threaded upon the nozzle 13 and its upper open end is contracted slightly over the tip 17, whereby the mixture of air and fuel will be directed in an effective manner upwardly from the nozzles into the mixing sleeve or tube 8, the nipple 19 being adjustable by screwing it upwardly or downwardly. Air will be drawn upwardly through the lower end of the sleeve 8 and mixed with the fuel to provide for the thorough combustion thereof, and the adjustment of the nipple 19 also provides for the regulation of the amount of

air admitted into the lower end of the sleeve 8. Thus, the lower end of the nipple 19 has an outstanding annular flange 20 providing a disk-valve adjustable to and from the lower inturned flange 22 of the sleeve 8. By adjusting the nipple 19 and its flange or valve 20 vertically, the flow of air through the opening surrounded by the flange 22 is adjusted.

In operation, the mixture is forced upwardly from the sleeve 8 against the bottom of the deflector 5, and is spread radially in all directions, between and past the ribs 4 and 7, thus providing an annular flame for heating the walls of the fire box in a thoroughly efficient manner. If desired, water can be allowed to drip onto the central portion of the deflector 5 from a pipe 23 above it, to keep the deflector 5 cool and to provide steam. Any water which flows from the center of the deflector 5 will shed into the annular trough next inside the flange on rib 6, and from which it evaporates or passes off as steam.

The burner above described is designed especially for high pressure, that is, of the pressure fluid, whereas the modification illustrated in Fig. 4 is for low pressure with a gravity feed of the fuel. In the modified form, a nipple 19' is provided within its contracted end portion with spiral or helical grooves 18' for creating a whirling motion of the pressure fluid, and the nozzle 15' extends through the contracted end of the nipple 19' and is directed to the side. Copies of this patent may be obtained for five cents each, by addressing the "Commissioner of Patents, Washington, D. C."

35
nipple 19 and has its end or tip tapered beyond the nipple.

Having thus described the invention, what is claimed as new is:

1. A hydrocarbon burner embodying a sleeve, a nozzle projecting into it and having 40 a tip, and a nipple adjustable on the nozzle adjacent to the tip thereof for controlling the discharge from the nozzle and having an outstanding flange providing a valve for controlling the flow of air into the sleeve. 45

2. A hydrocarbon burner embodying a sleeve having an inturned flange at one end surrounding an air inlet opening, a nozzle projecting into said end of the sleeve, and a valve adjustable upon said nozzle to and 50 from said flange.

3. A hydrocarbon burner embodying a sleeve having an inturned flange at one end, a nozzle projecting into said end of the sleeve and a second nozzle within the afore- 55 said nozzle, a tip between said nozzles, and a nipple adjustable upon the first mentioned nozzle and having a contracted end over-hanging said tip and an outstanding annular flange providing a valve adjustable to 60 and from the aforesaid flange.

In testimony that I claim the foregoing as my own, I have hereto affixed my signature in the presence of two witnesses.

GUY M. BARBER.
